UNITED STATES PATENT OFFICE.

JAMES McCARTHY AND JOHN McCARTHY PALMER, OF CHICAGO, ILLINOIS.

SAWING-MACHINE.

SPECIFICATION forming part of Letters Patent No. 738,623, dated September 8, 1903.

Application filed October 9, 1902. Serial No. 126,488. (No model.)

To all whom it may concern.

Be it known that we, JAMES McCARTHY and JOHN McCARTHY PALMER, citizens of the United States, residing at Chicago, in the county of Cook and State of Illinois, have invented a certain new, useful, and Improved Sawing-Machine, of which the following is a specification.

This invention relates to the type of machines in which a sliding or movable carriage is caused to reciprocate upon a stationary bed or base, said carriage or ram usually carrying the cutting tool or tools.

Our invention relates particularly to the above type of machine in which a circular cold-metal saw is the cutting-tool carried toward and from the work and is designed to be an improvement upon prevailing types of such machines, or, in other words, a practically new machine, so far as we are aware, which not only overcomes many of the well-known objections to the old forms of construction, but also embodies several novel and desirable features which have evidently not been thought of heretofore by the designers of the machines of this class now in general use.

The general objects of our invention are simplicity, to reduce the size of sawing-machines with a view to economizing floor-space, to secure easy accessibility to all the working parts, to overcome as far as possible a noisy and rattling operation of the parts, to dispense with the customary long main shaft splined full length and the bevel, miter, worm gears, or cones of gears sliding on a feather, and to obtain better and quicker work at a greatly-reduced cost.

Generally speaking, our invention consists in a rigid base or bed having an arm or bracket provided with a feed-screw journal-bearing and a carriage track or guideway, a carriage or ram slidably mounted upon and in said track or guideway provided with bearings for and carrying the main driving-shaft and parts mounted thereon, and also carrying the saw, the saw-driving means, and the saw-feeding means.

The invention further consists in a driving-drum for driving the main-shaft belt and the feed-screw-shaft belt.

The invention also consists in various de-

tails of construction and in combination of parts, all as hereinafter will be more fully described, and particularly pointed out in the claims.

The invention will be more readily understood by reference to the accompanying drawings, forming a part of this specification, in which similar figures refer to the same parts throughout the several views.

Figure 1 is a partly sectional view, with parts broken away, of a machine embodying my invention, same being taken substantially on the line *x* *x* of Fig. 2. Fig. 2 is a side elevation. Fig. 3 is an enlarged view of the feed-screw, showing the parts mounted thereon in section, said parts being broken away from the base or bed and the carriage. Fig. 4 is a side view of the ratchet and pawl and 65 a cross-section of the screw shown in Fig. 3, said pawl being raised and turned out of engagement with the ratchet-wheel. Fig. 5 is a top plan view of the machine minus the overhead drum and belts. Fig. 6 is a side 70 elevation of the carriage with the hood and side bearings or bracket broken away, the horizontal dotted lines showing the guide-grooves on the back of the carriage. The inclined dotted lines show the position of the 75 plate 14 of Fig. 9 on the front face of the carriage. Fig. 7 is a top plan view of the carriage with the saw-blade in position thereon. Fig. 8 is a horizontal sectional view through the center of the saw-driving combination 80 spur and antifriction-roller gear and the guide-plate of Fig. 9. Fig. 9 is a detail view of the aforesaid guide-plate. Fig. 10 is a fragment or section of the saw, showing the relative projection of the teeth. Fig. 11 illustrates the teeth of the saw, on an enlarged 85 scale, on a plane at right angles to that of Fig. 10. Fig. 12 is an enlarged view of the spur-gear, showing one of the pins and antifriction-roller. Fig. 13 is a section on the line 90 *y* *y* of Fig. 12. Figs. 14 and 15 are enlarged views of the saw-driving combination spur and antifriction-roller gear, showing a modification in the saw-slot thereof and in the method of mounting the roller-pins. Figs. 16, 17, 18, and 19 are detail views taken from Fig. 15.

In the drawings, A represents the base or bed, consisting of the upright portion 2, the

foot or bottom portion 4, (best shown in Fig. 5,) and the guide or track portion 3, all of which may, if desired, be cast in one piece. In the bottom 4 of the base is an oil channel 5 or trough 4', filled with oil and through which the saw-blade runs. The base 2 4 may be made in any suitable form, the essential feature being the track and guideway 3 thereof, which may be a separate part bolted to any 10 suitable support, and we do not confine our invention to the particular form shown of support for the track and guide 3. In the form of construction herein shown the base portion 4 supports an arch 4", which is provided 15 with a clamping-screw to hold the material to be sawed, the latter being shown in the form of a round bar in Fig. 2. The track or guideway 3 has a knife-edged or V-shaped lower edge 5, and a rectangular upper edge 6, fitting corresponding grooves or channels in the back of the carriage 7, this construction affording an easy and close fit of the parts, as well as sufficient bearing - surface for the weight of the carriage and its associated parts 20 to rest upon. The face of the guideway 3 is preferably depressed, as shown at 8, to avoid unnecessary friction between it and the carriage 7. The carriage 7 is provided with the main-shaft bearing member 8, the saw-shaft bearing 9, the raised portion containing a T-slot 10, adapted to engage the head of the bolt or shaft 11, upon which the combination spur and antifriction-roller gear is mounted. The holes 12 and 13 of the plate 14, Fig. 9, register with the slot 10 and the hole 15 of the main-shaft bearing 8. The carriage 7 is also provided with the lower extension or bearing-bracket 16, in which the shaft of the friction roller or pulley and its adjusting-shaft, hereinafter referred to, are journaled. Thus the carriage 7 supports and carries the following parts: The saw 17, the grooved combination spur and roller gear-wheel 18, having its spindle or shaft secured in the plate 14, the combination belt-pulley and friction-cone 19, the friction wheel or roller 20, the worm - gear hood 21, preferably an integral part of the part 16, the worm-gear and all of the shafts except the feed-screw 23, which has its stationary bearing in the arm 22, secured to the base or an integral part thereof. In order that the tension of the main driving-belt shall always be the same during the reciprocation or movement of the carriage, we provide a 45 driving-drum 24, which drives the main driving-belt 25 and permits it to move with the carriage. Said drum 24 is mounted in a plane parallel with that in which the carriage moves and the belt therefore given a quarter-twist. 50 The main-shaft pulley is preferably provided with double flanges, as shown, to prevent the belt from slipping off in case of any slight discrepancy in the relative positions of the driving - drum 24 and the coned pulley 19. 55 A belt 26, also driven by the drum 24, is provided for rotating the feed-screw 23 for a quick return of the carriage 7. The belt 25 oper-

ates the slow or worm-gear feed movement upon the stationary screw, while the belt 26 rotates the screw itself in the threaded hole 70 of the worm-gear, as will hereinafter be more fully explained. The drum 24 is made of sufficient length to permit the belt 25 to travel with the carriage the full distance both ways and also extends far enough to provide for 75 the belt 26.

The combination belt-pulley and friction-cone 19 is provided with an internal hub 27', which is slidably mounted upon the main shaft 27 for a slight movement in the plane 80 of the long axis of said shaft 27 by means of a feather-key 28, screw-threaded into the hub 27' and longitudinally movable in the slot or key-seat 28' of the main shaft 27. Around the shaft 27 is a spiral spring 28", compressed 85 between the hub 27' and a collar 29, preferably shrunk upon the shaft 27. A collar 30 is keyed or shrunk upon the outer end of the shaft 27, which, together with the collar 29, prevents longitudinal movement of the shaft 90 27 in its bearing 8. Between the collar 29 and the inner face or end of the bearing 8 and secured on the shaft 27 is the wide gear 32', which drives the combination spur and roller-pin gear 31, provided with the deep groove or 95 peripheral channel 32. (Best shown in Fig. 8 and the modified Fig. 15.) This groove or channel is slightly wider than the thickness of the saw-blade of the saw 17. This groove may be of uniform width throughout or its 100 outer portion may be enlarged, as shown in Fig. 15, to provide more room for any metal particles or chips which may adhere to the saw-blade or drop therefrom between the sides of the groove. Circularly arranged near the bottom of the groove 32, as clearly illustrated in Figs. 2 and 14 and in detail in Fig. 12, is a row of antifriction-roller pins 33, which may be short screw-bolts, as illustrated in Fig. 12, or plain pins flush with the sides of the gear and 110 provided with bushings, as illustrated in Fig. 15, or any suitable means for holding the pins in position may be provided. Loosely mounted for rotary movement upon the pins 33 are the antifriction rollers or collars 34, Figs. 12 115 and 13. In Fig. 15 the roller-pins 33' are shown mounted in bushings 35, provided with oil-holes 36. Also mounted on the shaft 27, between the combination-gear 31 and the bearing 8, is the adjusting-plate 14, movable in 120 the plane of an arc with the shaft 27 as its center, which when secured in position is clamped to the T-slot 10 of the carriage 7 between the head of the bolt or spindle 11 and the bushing 11', upon which the gear 31 is 125 mounted. A washer or ring 11" and the nut 11''' complete the clamping means, which rigidly secure the plate 14 and the gear 31 to the carriage 7. The position of plate 14 is clearly illustrated by dotted lines in Fig. 6, 130 and the plate itself is in the detail view of Fig. 9, the hole 12 being for the spindle or bolt 11 and the hole 13 for the main shaft 27.

Opposite the main-shaft bearing 8 and the

bearing 9 for the saw is the upwardly-extending portion 16 of the carriage, its relative relation with regard to the carriage being best shown in Fig. 7, as also in Fig. 1, 5 same being broken away in the carriage illustration, Fig. 6. In this side extension of the carriage are bearings or shaft-sockets 37 and 38 for the friction-roller shaft 39 and for the lower or journal end of adjusting-screw 40 10 by means of which the friction-roller 41 is adjusted in varying positions along the face of the cone 19 for regulating the degree of speed of the carriage-feeding mechanism. The screw 42 is provided with a threaded 15 nut 43, to which is secured an adjusting-fork 44, engaging a groove 41' in the friction-roller 41 and through which the said roller is moved up and down along the shaft 39. In the roller 41 is a key which slides in the key-seat 20 39' of the shaft 39. Said key is not shown in the drawings. Bolted to the hood portion 21 of the member 16 of the carriage or secured thereto by any suitable means is a disk 46, which forms one side of the hood and one of the 25 side bearings for the combination worm-gear and nut 45 and is clearly illustrated in Fig. 3. The disk 46 is provided with a circular opening of just sufficient size to admit the feed-screw 23. The socket or journal-box 37 in 30 the carriage member 16 is interrupted or made in two parts by the opening 47 in the member 16 to provide a seat for the worm 48, which is secured to the shaft by a counter-sunk set-screw or any other suitable means. 35 The worm 48, therefore, also serves as a collar to hold the shaft 39 against any but rotary movement in the socket 37. A collar 49, secured by a set-screw, performs the same office for the shaft 40 of the adjusting-screw 40 42. A hand-wheel 50 is provided on the screw 42 for rotating it, and thereby varying the speed of the friction-roller 41 or moving it between the apex and base of the cone 19. The worm 48 operates the worm-gear 45, having 45 threaded engagement with the screw 23. (See Fig. 3.) Said worm-gear is caused to rotate around the screw 23 for the varying degrees of feed movement imparted to it through the cone 19, the friction-roller 41, and the worm 48 upon the shaft thereof, and the feed-screw 23 is caused to rotate within the worm-gear 45 for the quick return movement, thus serving to impart two movements, which may be combined, if desired, to obtain a large 50 range of differential feed movement in connection with suitable driving-belt connection, and this arrangement also provides for the thrust against the screw-threads being always in the same direction whether the carriage is 55 fed slowly forward or returned quickly, doing away with play between the threads of the screw 23 and the combination worm-gear and nut 45 during the reciprocation of the carriage. The worm-gear 45 has a stub 51, 60 which is threaded for the fiber-collar 52 and the lock-nut or threaded collar 52'. An additional threaded collar or lock-nut 53 may

also be provided. The hood 21, being a part of the member 16 of the carriage and bearing against both sides of the worm-gear and nut 45, will obviously be carried therewith, together with the carriage itself and all the parts mounted thereon, as the worm-gear rotates around the feed-screw or the latter rotates within the former. The stationary bearing for the screw 23 is in the bracket or arm 22, extending from one end of the base 2. A portion of this arm is shown in Figs. 1 and 3, a front view thereof in Fig. 2, and a top view thereof in Fig. 5. The form of this arm or 75 80 the manner of its attachment is not an essential feature of our invention, and any suitable support for the end of the screw 23 will serve the purpose.

Upon the screw 23, bearing against the left 85 side of the bearing or arm 22, Fig. 3, is a ratchet-wheel 54, which is preferably shrunk upon the screw-shaft. Engaging the teeth of the ratchet-wheel 54 and supported for rotary movement as well as longitudinal movement 90 in a bearing 55 in the top of the arm 22 is a pawl 56, the point of which may be inclined on one side, as shown, to permit the teeth of the ratchet-wheel to slip over the point of the pawl when the screw is rotated in the 95 worm-gear and nut 45 for a quick return movement, while the other side of the pawl is inclined toward the ratchet-teeth and holds the feed-screw stationary when the carriage is fed forward. If it is desired to feed the 100 carriage both ways by a slow movement, the pawl and ratchet may be made to hold the screw against rotation in both directions or the beveled side of the pawl alternately reversed with relation to the ratchet-teeth. 105 The upper end of the pawl is provided with a knurled head or button 57, in which is a downwardly-extending socket-pin 58, (see Fig. 4,) adapted to slip into a small hole or opening 59. (Shown in Fig. 3.) By lifting 110 the pawl and turning it into the position shown in Fig. 4 the pin 58 is lifted out of the opening 59, which will rest upon the top 60 of the socket 55 and keep the point of the pawl out of engagement with the teeth of the 115 ratchet, thus permitting the feed-screw 23 to turn in either direction.

Bearing against the right-hand side of the arm 22, Fig. 3, and screw-threaded upon the end of the feed-screw 23 are collars or nuts 120 61 and 62, the latter serving as the lock-nut. By means of these collars and the shoulder 23' of the feed-screw a close adjustment can be made and any wear taken up. On the stationary bearing end of the feed-screw are 125 fixed and loose pulleys 63 64, over which the belt 26 runs to rotate the screw for a quick return or to run idly. Of course the carriage may be rotated in either direction and any suitable belt connection or arrangement provided for its pulleys 63 and 64. The extreme end of the feed-screw outside of the fixed and loose pulleys is squared to permit of turning the screw by hand with a wrench or crank. 130

The dotted lines, Fig. 3, indicate one method of providing an automatic belt-shifter to throw the belt from the tight to the loose pulley when the carriage has reached its extreme 5 starting-point in a quick return movement. In practice, however, this is not deemed necessary, as the force required to return the carriage would not necessitate much tension in the belt, which would readily slip if the operator neglected to throw the belt onto the loose pulley in time, and no damage to the machine would therefore be caused by such neglect.

Referring now to the construction of the 15 saw-blade teeth illustrated in Figs. 10 and 11, two sets of teeth, having their cutting-points arranged in concentric circles, are provided. The projecting or longer teeth 65 are tapered, so as to present a smaller cutting-point than 20 the inner row of teeth 66. The object of this is to strengthen the initial cutting-teeth 65 with relation to the amount of resistance or work imposed upon it and to constitute it a sort of entering wedge, cutting a channel and 25 oiling said channel for the teeth 66 cutting to full width, making room for the metal to expand into the groove when engaged or sheared off by the full-width teeth 66. By providing the saw-blade with the tapered or V-shaped 30 leader-teeth the blade is led straight through the work, as well as providing an oil-channel and expanding-space for the final cut, which on account of the room for expansion enables the saw-blade to make a much smoother cut 35 through the work than when the blade fits tightly in the cut and largely prevents lubrication, causing great frictional heat and wear upon the teeth. Our invention provides for a liberal and constant lubrication of the saw- 40 cut, keeps the saw cool, enables a greater speed of operation thereof, prolongs the life of the saw, and obviates the frequent regumming made necessary in connection with the common form of saw-teeth.

45 The operation of our sawing-machine with the source of power or belt connections arranged as shown in the drawings is as follows: The drum or long driving-pulley 24 having been started in rotation in the direction of 50 the arrow, the belt 25 on the cone-faced pulley 19 will drive the latter in the direction of the arrow, and with it the small spur-wheel 32, which engages the peripheral teeth of the combination spur and roller gear 18, driving 55 same in the opposite direction, the rollers 34 of which are in mesh with the teeth of the saw and rotate it in the same direction as the friction-cone. At the same time the friction-cone 19 operates against the friction-roller 41, and rotates the shaft thereof, together with the worm 48 on said shaft. It being assumed 60 that the belt 26 is on the outer or loose pulley instead of the tight pulley, as shown in Fig. 2, the worm being in engagement with the 65 worm-gear 45 will rotate the latter at a comparatively slow rate of speed around the feed-screw 23 to drive the carriage forward. If a

higher or a lower rate of speed of the carriage is desired, the operator will turn the screw 42 by means of the hand-wheel thereon and 70 through the fork 44 move the friction-roller 41 either toward the base of the cone or toward its apex. As the spiral spring 28' presses the friction-cone outward in a horizontal plane and the friction-roller surface 75 lies in a plane which intersects that of the outward movement of the cone the tendency is to not only press the latter against the friction-roller, but to wedge it against or upon the friction-roller 41, which makes the frictional 80 contact or engagement between the respective friction-surfaces far greater than could be secured by straight pressure. As is also evident, the friction-cone affords infinite variations in speed as compared to speed variation 85 through cones of gears and is noiseless in contradistinction to the latter. When the operator desires to return the carriage, he will throw the belt 26 onto the tight pulley which rotates the feed-screw in the threads of the 90 worm-gear in a direction opposite to that in which the pawl engages the ratchet-teeth, and the pawl slips over the teeth during the return movement, the tendency of the worm gear and nut being to turn the screw in the 95 opposite direction when rotating around it. Of course under the arrangement shown in Fig. 2 the worm-gear is constantly rotating around the screw, tending to feed the carriage forward even when it is being returned; 100 but, as is also evident, the forward movement imparted by the worm-gear rotating around the screw is insignificant compared with the speed imparted to the worm gear or nut when the screw is rotated therein. The distance 105 the carriage is moved on its return being usually small, the operator may prefer to turn the screw by hand instead of throwing the belt 26 onto the tight pulley, in which case he would have recourse to a crank or wrench 110 fitting the square end of the feed-screw, and if he wishes to accelerate the forward motion of the carriage by hand in like manner he may do so by lifting the pawl out of engagement with the ratchet-teeth, as shown in Fig. 115 4. It is also evident that the friction-roller 41 may be moved down on the shaft 39 far enough to be thrown out of engagement with the friction-cone entirely and provide for feeding by hand only by making the threads 120 on the screw 42 a little longer than as shown in Fig. 1. As the saw revolves and the teeth thereof dip through the oil in oil-receptacle 4' oil is carried up on the teeth and deposited 125 in the saw-cut, as previously described.

Our machine is adaptable to a large number of other purposes aside from sawing metal, where a sliding carriage is employed, especially the carriage-feed and return mechanism.

13 It is obvious that numerous modifications may be made in our invention by one skilled in the art without departing from the spirit of same, and we therefore do not confine our

invention to the particular constructions and uses herein shown and described.

Having described our invention, we claim as new and desire to secure by Letters Patent—

5 1. The combination, with a suitable support, of a reciprocatory carriage thereon, a normally stationary feed-screw in said carriage and support, a driving and a driven shaft mounted on said carriage, a friction-cone splined to said driving-shaft, a friction-roller coöperating therewith, splined to said driven shaft, means for forcing said cone and roller against each other, means for adjusting said roller along the face of said cone, a 15 worm on said driven shaft, and a worm-gear threaded on said screw, engaging said worm and rotatively held in said carriage.

2. The combination, with a suitable support, of a reciprocatory carriage slidable thereon, a feed-screw journaled in said support, a ratchet-wheel fixed on said screw, a pawl adapted to engage same adjustably mounted in said support, a driving and a driven shaft journaled in said carriage, a pulley and friction-cone splined to said driving-shaft, an adjustable friction-roller and a worm splined to said driven shaft, means for forcing the friction-surfaces of said cone and roller against each other, means for adjusting 25 said roller along the face of said cone, a worm-gear threaded on said screw, a hood therefor secured to said carriage, a suitably-driven belt for said pulley and means for moving said belt with the carriage.

3. The combination, with a suitable support, of a feed-screw journaled therein, a carriage slidably mounted on said support, means for rotating said screw in one direction and a ratchet-wheel and pawl normally holding it against rotation in the opposite direction, a saw-carrying shaft and a carriage-reciprocating shaft each journaled in said carriage, a worm-gear threaded on said screw and a hood therefor mounted in said carriage, a saw on said saw-carrying shaft, a combination friction cone and pulley and a gear splined on said driving-shaft, a double gear meshing with said gear and engaging both sides of said saw, means for adjusting 45 same angularly with relation to said driving-shaft, a friction-roller and a worm splined on said carriage-reciprocating shaft, arranged, respectively to be rotated by said cone and to rotate said worm-gear, elastic means for forcing said cone against said friction-roller and means for adjusting the latter along the face of said cone, a belt for said pulley and driving means therefor permitting said belt to move with said carriage.

60 4. The combination of a reciprocatory carriage having a driving-shaft and a saw-carrying shaft mounted thereon, a saw on said last-mentioned shaft, a spur-gear on said driving-shaft, and a double gear meshing therewith and engaging both sides of and meshing with the teeth of said saw.

5. The combination of a reciprocatory car-

riage, having a driving-shaft and a saw-carrying shaft mounted thereon, a saw on said last-mentioned shaft, a gear on said driving-shaft, 70 a double gear meshing therewith and engaging both sides of the saw, said double gear being provided with a circular series of anti-friction saw-teeth-engaging rollers.

6. The combination, of a reciprocatory carriage, having a driving-shaft and a saw-carrying shaft mounted thereon, a saw on said last-mentioned shaft, a gear on said driving-shaft, and a double gear meshing therewith and engaging both sides of the saw, said double gear 80 being provided with a circular series of anti-friction saw-teeth-engaging rollers held in bushings removably mounted in the sides of said double gear.

7. The combination of a reciprocatory carriage, having a driving-shaft and a saw-carrying shaft mounted thereon, a saw on said last-mentioned shaft, a gear on said driving-shaft, a double gear meshing therewith and engaging both sides of the saw, said double 90 gear being provided with a circular series of anti-friction saw-teeth-engaging rollers held in bushings removably mounted in the sides of said double gear, and a bearing-arm carrying said double gear, pivoted upon the driving-shaft and adjustably held in said carriage.

8. The combination of a reciprocatory carriage, having a driving-shaft and a saw-carrying shaft mounted thereon, a saw on said last-mentioned shaft, a single gear and a combination pulley and friction-cone on said driving-shaft, a double gear meshing with said single gear and the saw and also supporting both sides of the latter, and a carriage-reciprocating mechanism driven by said cone. 105

9. The combination, with a stationary support, of a reciprocatory carriage, having a driving-shaft, a saw-carrying shaft and a carriage-reciprocating shaft mounted thereon, a saw on said saw-carrying shaft, a single gear and 110 a combination pulley and friction-cone on said driving-shaft, a cone-engaging friction-roller and a worm splined on said carriage-reciprocating shaft, means for adjusting said roller along the face of said cone and means for forcing the latter against said roller, a double gear meshing with said single gear and engaging both sides of the saw, said double gear being provided with a circular series of anti-friction saw-teeth-engaging rollers held in bushings 115 removably mounted in the sides of said double gear, a screw journaled in said support, a worm-gear threaded thereon, said worm-gear being mounted in a hood on said carriage and meshing with said worm.

10. The combination of a suitable support provided with guideways, a reciprocatory carriage mounted thereon and carrying a driving-shaft, a driven pulley and driving friction-cone splined to said shaft, means upon said shaft and carriage for guiding and rotating a circular saw, a carriage-driving friction-roller adjustably mounted and arranged to be rotated by said friction-cone, a spring tending

to force said cone against said roller, means 5 for moving said friction-roller along the face of said friction-cone from its apex to its base, for the purpose of varying the speed of movement of the carriage, and means upon said support coöperating with said carriage-driving means.

11. The combination of a suitable support, a reciprocating carriage thereon, a driving-shaft and a saw-carrying shaft mounted on said carriage, a saw on said last-mentioned shaft, a gear and a spring-pressed, longitudinally-movable combined friction-cone and pulley on said shaft for driving the saw and 15 the carriage-reciprocating mechanism, the double gears interposed between and meshing with said gear and saw, a feed-screw mounted in said support, and means coöperating therewith and with said cone for reciprocating the carriage.

12. The combination of a suitable support provided with guideways, a reciprocating carriage mounted thereon, a cutting-tool and carriage-driving shaft mounted in said carriage and provided with a combined friction-cone and pulley, a friction-roller mounted adjustably for rotation by said cone, whereby the speed of the carriage movement is made variable, a shaft for said friction-roller, a worm 25 on said shaft, a worm-gear in mesh with said worm, a feed-screw for the carriage on which said worm-gear is threaded, a cutting-tool on the carriage driven by said driving-shaft, a belt for transmitting power to said cone and 30 pulley, and means whereby said belt may be moved with said carriage.

13. The combination of a suitable support,

having guideways, a reciprocating carriage thereon, having a driving-shaft and a saw-carrying shaft, a feed-screw journaled in said support, means for rotating said screw and means for holding it stationary, a worm-gear threaded on said shaft, having a hood secured to said carriage, a friction-rollershaft, a worm thereon in mesh with said worm-gear, a longitudinally-movable friction-roller splined on said roller-shaft, an adjusting-screw and means for moving said roller thereby along said roller-shaft, a combined belt-pulley and friction-cone and a saw-driving gear on said 45 driving-shaft, said friction-roller being arranged to be rotated by said cone and moved along the face thereof by said adjusting-screw, a bearing-arm pivoted on said main driving-shaft, a double gear meshing with 50 said saw-driving gear and engaging both sides of the saw, said double gear being mounted on the free end of said bearing-arm and provided with a circular series of antifriction saw-teeth-engaging rollers held in bushings 55 removably mounted in the sides of said double gear, means for adjustably securing the free end of said arm upon the carriage, means for oiling said saw, a belt for said pulley and a drum for driving said belt.

In testimony whereof we have hereunto subscribed our names, in the presence of two witnesses, this 30th day of September, 1902.

JAMES McCARTHY.
JOHN McCARTHY PALMER.

In presence of—
MAX BAUM,
PAUL GERHARDT.
